(57) **CLAIM**

I claim, the ornamental design for a spring loaded disposable glove dispenser, as shown and described.

DESCRIPTION

FIG. 1 is a side and top perspective view of a spring loaded disposable glove dispenser showing my new design.

FIG. 2 is a side elevation view thereof.

FIG. 3 is a top plan view thereof; and,

FIG. 4 is a bottom plan view thereof.

The broken lines in the drawings are for the purpose of illustrating environmental features which form no part of the claimed design.

1 Claim, 4 Drawing Sheets

FIG. 1

FIG. 2

FIG. 3

FIG. 4
